UNITED STATES PATENT OFFICE.

MICHAEL EDWARD WILSON, OF DETROIT, MICHIGAN.

DIRECTION-INDICATOR FOR AUTOMOBILES.

1,311,257.

Specification of Letters Patent. Patented July 29, 1918.

Application filed January 16, 1917. Serial No. 271,275.

To all whom it may concern:

Be it known that I, MICHAEL EDWARD WILSON, a citizen of the United States, residing at Detroit, in the county of Wayne and State of Michigan, have invented certain new and useful Improvements in Direction-Indicators for Automobiles, of which the following is a specification, reference being had to the accompanying drawings.

10 This invention relates to direction indicators for automobiles and particularly to that type of indicator wherein a signal arm is adapted to be projected from one side of the vehicle or the other to indicate the direction which the automobile is about to take.

The general object of this invention is to provide an extremely simple construction of this character having the form of a hand and which is adapted to lie flat against the body of the automobile and to therefore be entirely inconspicuous when in an inoperative position but which may be turned outward to a display position and particularly to provide a signal of this character adapted 25 to be attached to the side wall or door of the automobile and to extend downward from the top of this wall and to lie flat against the outer surface of the wall and provide mechanism whereby the actuation of a handle in one direction will cause the signal hand to move upward from a vertical to a horizontal position at right angles to the wall and will also cause the hand to rotate so that the sheet metal of which the hand

30 is made extends vertically and in a display position to those in the rear or front of the automobile.

A further object is to provide a construction of this character which may be readily 40 applied to all makes of automobiles and which is adapted to be used either with or without operating treadles or levers.

A further object is to provide a device of 45 this character which is latched when it is in its outwardly projected position and which is assisted in its return to its inoperative position by a spring.

Other objects will appear in the course of the following description.

My invention is illustrated in the accompanying drawings, wherein:—

Figure 1 is a vertical section of an automobile wall showing my signal applied thereto;

Fig. 2 is a front elevation of the signal or indicator;

Fig. 3 is a vertical sectional view thereof;

Fig. 4 is a section on the line 4—4 of Fig. 3; and

Fig. 5 is a perspective view of the housing.

Referring to these drawings, it will be seen that my construction comprises a base 10 adapted to fit against the top of the wall A of an automobile and having clamps 11 attached thereto adapted to engage the wall, 55 said clamps having opposed jaws, one of the jaws 12 being fixed and the other jaw including a set screw 13 opposed to the fixed jaw.

Riveted to the base and extending therefrom at right angles to the base is the housing 14 which is made of sheet metal or like material and which is approximately U-shaped in vertical section. The inner end of this housing is open as at 15 and its outer end is also open. One wall of the housing 70 is cut away on the line 16. Passing through the housing is a pivot pin 17 and the opposite walls of the housing are each formed with an annular depression 18 having opposite extensions 19. The material of the 75 housing is resilient so that the side walls of the housing will yield somewhat.

Mounted upon the pivot pin 17 is an approximately U-shaped member 20, which fits closely between the upper and lower walls 80 of the housing, and is formed to provide two outwardly extending parallel arms 21 perforated for the passage of a stud bolt or spindle 22, forming part of and an extension from a bracket 23. This bracket at its end 90 opposite the spindle 22 is widened as at 24 and riveted to this wide extremity is the sheet metal semaphore 25 which, as before stated, is approximately in the shape of a human hand. Between the spindle 22 and 95 the bracket proper 23 is a cylindrical portion 26 formed to provide an outwardly projecting, transversely extending lug 27. Sur-

rounding the spindle 22 and disposed between the arms 21 of the member 20 is a coiled torsion spring 28, one end of which is fastened to the body 20, the opposite end being fastened to the spindle 22. Attached to the body 20 and extending in a vertical plane therefrom upward and laterally and then directly upward is a handle 29.

In the practical use of this device it is applied as indicated upon the wall or door of an automobile and is clamped thereto by the movable clamping jaw 13. The handle 29 when the signal is in its inoperative position extends upward and the signal 25 extends downward and lies flat against the outer face of the wall or door. The outer face of the signal is painted the same color and shade as the body of the automobile, so that when this signal lies flat down against the outer face of the wall it is not conspicuous or particularly observable. The inner face however may be painted white, red or any other desired conspicuous color.

Now when it is desired to indicate that the automobile is about to turn to the right or to the left, as the case may be, the handle 29 is drawn downward to a horizontal position, and the pressure exerted upon the handle causes the depressed portion 30 on the body 20 to move out of the depressions 19 of the housing, springing the housing slightly in doing so. As the handle is further rotated, the signal 25 swings upward until the lug 27 engages with the angular edge 16 of the cut-away portion on one wall of the housing. When this lug strikes this angular portion which constitutes a cam the spindle will be rotated against the force of the spring 28 so as to turn the hand or signal around the axis of the spindle 22 and bring it to display position. When the signal has been brought to a full display position, that is into a vertical plane transverse to the direction of motion of the vehicle, the grooves 30 have engaged with the depressions 19 and the signal will thus be locked in its display position. The signal will remain in this position as long as desired. When it is desired to retract the signal the handle is pushed in the reverse direction and as soon as the lug 27 has escaped the edge 16 the spring 28 causes the spindle to rotate to return the signal and then as the handle is moved still farther over, the signal is returned to a position where it lies flat against the outer face of the side wall of the vehicle in the manner indicated in Fig. 1.

It will be seen that the device above described is entirely positive in its action and that it is extremely simple both in operation and in construction. While I have illustrated a base formed with clamps which may be attached to the wall or door of an auto-

mobile or any other suitable position it will, of course, be understood that the bases can be made for permanent attachment to the car and thus the signal made as part of or initially with the car body. It is further pointed out that the housing 14 constitutes not only a housing but that it forms a spring lock for holding the signal in its projected or contracted position and that it is the edge 16 of this housing which in conjunction with the lug 27 forms the means whereby the hand is automatically turned to its display position. When it is in its retracted position, the mechanism offers but very slight wind resistance and it will be obvious that when it is being shifted to its display position it offers but a minimum wind resistance until it is fully turned. The device may be made for either the right hand or left hand side of the vehicle, and either one hand may be used to indicate the fact that the vehicle is about to turn without indicating the particular direction, or two signals may be used, one on each side of the machine.

It is to be noted that the lug 27 has a square rear corner 27^a, as illustrated most clearly in Fig. 4 which will abut against the side wall of the casing 14 in the manner illustrated in Fig. 4 when the parts are retracted to the position shown in Fig. 3. This prevents the signal from turning completely around when it is retracted, that is when it is returned to its inoperative position it will be parallel to the wall of the vehicle. It will be understood that the pivot 17 is to be part of the casting or forging 20 and forms practically trunnions extending from this member 20. Further, the parts 22, 23 and 24 are preferably made in one piece or forging with the lug 27. However, these details may be varied when necessary or advisable.

It is to be understood, of course, that this device is adapted for use on other vehicles besides automobiles, and further I do not wish to limit myself to the use of a hand operated signal, as it is obvious that the handle 29 or an equivalent part may be connected either to a lever on the steering post of a machine or to an operating pedal. While I have illustrated a construction which I have found to be thoroughly effective in actual use, which is strong, simple and cheap to manufacture, yet it is obvious that many changes might be made in the details of construction and arrangement of parts without departing from the spirit of the invention.

I claim:-

1. An automobile signal including a housing having means whereby it may be attached to the top of an automobile wall and having resilient side walls formed with oppositely disposed depressions, a body mounted

between said side walls and having crossed ribs adapted to engage in said depressions, the body being pivoted to the housing on an axis extending through the intersection of 5 said crossed ribs, and having means whereby it may be rotated within the housing, a rotatable spindle mounted in the body and extending at right angles to the axis of the body, a semaphore attached to said spindle 10 and rotating therewith, means causing a rotation of the spindle as the body is turned to swing the semaphore away from the wall of the vehicle, and a spring resisting said rotation of the spindle and urging the 15 spindle in a reverse direction to thereby return the semaphore to a position parallel to the wall of the vehicle.

2. A direction indicator for automobiles comprising a housing having resilient laterally spaced walls and having means whereby 20 it may be attached to the wall of a vehicle, a U-shaped body mounted between the walls of the housing and having a pivot pin passing through said walls, the confronting faces 25 of the walls of the housing and the body being formed with coacting depressions and ribs to hold the body in its rotated positions, a spindle mounted in the arms of the body and extending at right angles to the axis 30 thereof, a semaphore attached to said spindle, and means causing a rotation of the spindle in one direction as the body is turned to swing the semaphore away from the wall of the car and causing a rotation of the 35 spindle in the opposite direction as the body is turned to swing the semaphore toward the body of the car.

3. A direction indicator for automobiles comprising a housing having resilient laterally spaced walls and having means whereby 40 it may be attached to the wall of a vehicle, a U-shaped body mounted between the walls of the housing and having a pivot pin passing through said walls, the confronting faces 45 of the walls of the housing and the body being formed with coacting depressions and ribs to hold the body in its rotated positions, a spindle mounted in the arms of the body and extending at right angles to the axis 50 thereof, a semaphore attached to said spindle, means for causing a rotation of the spindle in one direction as the body is turned to swing the semaphore away from the side of the car and cause the semaphore to be 55 rotated to a vertical plane, and a spring resisting said rotation of the spindle and semaphore and causing the reverse rotation of the spindle and semaphore to turn the semaphore flat against the side of the car 60 when the body is swung to carry the semaphore toward the car.

4. A direction indicator for automobiles comprising a housing having resilient upper and lower walls and having means whereby

it may be attached to the wall of the vehicle, 65 a U-shaped body mounted between the upper and lower walls of the housing and having a pivot pin passing through said walls, the upper and lower walls of the housing and the body being formed with coacting depressions and ribs to hold the body in its rotated positions, a spindle mounted in the arms of the body and extending at right angles to the axis thereof, a semaphore attached to said spindle, a lug carried by the 70 spindle and projecting therefrom, the housing being formed to provide a cam-like projection disposed in the path of said lug to cause a rotation of the spindle in one direction as the body is swung to carry the semaphore away from the wall of the car, and a spring disposed between said arms engaged with the body at one end and with the spindle at the other resisting the rotation of the 75 spindle and causing a reverse rotation of the 80 spindle and semaphore when the body is swung to carry the semaphore toward the wall of the car.

5. The combination with a vehicle having a side wall, of a member mounted upon the 90 side wall for swinging movement in a vertical plane, a signal semaphore mounted upon said member for movement around a longitudinal axis at right angles to the plane of rotation of said member, said signal semaphore in an inoperative position extending downward and lying flat against the side wall of the car, means for swinging said body around its axis to move the semaphore to a horizontal position, and means for rotating the semaphore around its longitudinal 95 axis in one direction as the semaphore is swung away from the body of the car to thereby rotate it to a display position and swing the semaphore in a reverse direction 100 into parallel relation to the body of the car as the member is swung in the other direction to carry the semaphore downward.

6. An automobile signal including a member having means of attachment to the wall 110 of a vehicle, a U-shaped member rotatably mounted upon the supporting member for movement in a vertical plane and having a handle normally projected upward, a spindle extending at right angles to the axis of the 115 U-shaped member and rotatably mounted in the legs thereof and normally extending downward and carrying at its lower end a signal, said signal being normally disposed in a plane at right angles to the plane of 120 rotation of the U-shaped member, said spindle having a laterally projecting lug, a coiled spring attached to the U-shaped member and to said spindle and urging the spindle in a direction wherein the signal is at right angles to the plane of rotation of the U-shaped member, the spindle having a laterally projecting lug and the supporting member hav-

ing a projection with which said lug engages as the U-shaped member is rotated to lift the signal whereby the spindle and signal are rotated through a quarter of a revolution 5 when the spindle and signal are disposed in a horizontal plane.

In testimony whereof I hereunto affix my signature in the presence of two witnesses.

MICHAEL EDWARD WILSON.
